FILE HOLDER

Aldo F. Burnell, Eustis, Fla.

Application September 3, 1940, Serial No. 355,245

2 Claims. (Cl. 29—80)

This invention relates to a file holder and has for an object to provide a base through the medium of which two files may be mounted on the holder in order to finish metal turret tops, door panels and the tops of hoods of automobile bodies in less time, with less waves, and without forming sharp marks in the metal which are the objectional features of the single file holder used in automobile body work.

A further object is to provide apparatus of this character which will be formed of a few strong, simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming a part of this specification:

Figure 1 is a side elevation of a file holder constructed in accordance with the invention.

Figure 2 is a bottom plan view of the file holder with a portion of both files broken away to expose the base.

Figure 3 is a cross sectional view taken on the line 3—3 of Figure 1 drawn to large scale.

Figure 4 is a perspective view of the base.

Referring now to the drawing in which like characters of reference designate similar parts in the various views, the base is shown to comprise two substantially rectangular resilient metal bars 10 connected together at the ends by metal plates 11, which are disposed on top of the longitudinal bars 10. The base so constructed is thicker at the ends than at the center and thus the base is rigid at the ends and very flexible and resilient between the ends so that it may be shaped to the contour of metal to be filed. The end plates 11 are preferably secured to the longitudinal bars 10 by brazing, although other securing means may be employed. The longitudinal bars are spaced apart at their confronting longitudinal inner edges to provide a slot 12 through which filings may drop through the base.

The base is provided preferably with three openings 13 at each end. The outer openings receive bolts 14 through the medium of which two files 15 are secured against the bottom faces of the longitudinal resilient bars 10, on either side

5 of the slot 12, as best shown in Figure 2. The intermediate openings receive respective screws 16 which secure the conventional handles 17 of a file holder upon the top faces of the end plates 11, as best shown in Figure 1.

As is conventional the handles 17 of the file holder are connected by a turn buckle 18 which may be operated to bend the resilient longitudinal bars 10 of the base to fit any desired contour 10 of the work.

The base constructed as above described carries two files in laterally spaced relation to each other so that filings may drop through the slot 12 of the base and in practice it has been found 15 that the use of two files carried by the above-described base performs the work in quicker time than is ordinarily accomplished by one file and in addition the metal is finished with less waves than with a single file. It is also found that the base will not weave and allow sharp marks to be 20 formed into the metal as is encountered when a single file is used.

From the above description it is thought that the construction and operation of the invention 25 will be fully understood without further explanation.

What is claimed is:

1. An automobile body file holder base for securing two files to a holder, said base being substantially rectangular in plan and being formed of resilient material, said base having a central longitudinal slot terminating short of the ends of the base, said base being provided at each 30 end with a series of openings, one opening of each series being adapted to receive means for securing the base to a holder and the remaining openings of the series being adapted to receive means for securing files at the ends to the base on opposite sides of said slot.

2. The combination with an automobile body file holder having handles connected together by a turn buckle, of a file holding base including longitudinal resilient bars spaced apart at their 45 inner confronting longitudinal edges to provide a slot, plates secured to the upper faces of the bars and connecting the bars together at the ends, two files disposed to extend longitudinally on the bottom faces of the bars on opposite sides of the slot, means securing the files to the end plates, and means securing the end plates to the handles of the holder.

ALDO F. BURNELL.
